OTTO M. BIRELEY, OF INDIANAPOLIS, INDIANA, ASSIGNOR TO HARRY RYBOLT, OF INDIANAPOLIS, INDIANA, DOING BUSINESS UNDER THE NAME OF RYBOLT HEATING COMPANY.

SECTIONAL LINING FOR FIRE-BOWLS.

1,199,045.

Specification of Letters Patent. Patented Sept. 26, 1916.

Application filed May 22, 1916. Serial No. 99,181.

To all whom it may concern:

Be it known that I, Otto M. BIRELEY, a citizen of the United States, residing at Indianapolis, in the county of Marion and State of Indiana, have invented certain new and useful Improvements in Sectional Lining for Fire-Bowls, of which the following is a specification.

This invention relates to improvements in cast iron linings for the fire pots of furnaces and stoves, and the object of the invention is to provide a lining in separately removable sections so constructed as to reduce the tendency to warp and burn out to a minimum, and always easily removable when damaged by the heat, and which will protect the fire pot, prolong the life of the furnace and facilitate and cheapen repairs to that part which is subject to the greatest deterioration.

I accomplish the above, and other objects which will hereinafter appear, by the mechanism illustrated in the accompanying drawing, in which—

25 Figure 1 is a vertical section of a fire pot and lining therefor embodying my invention, the section being on the line 1—1 of Fig. 2. Fig. 2 is a top plan view of same. Fig. 3 is an elevation looking at the inner side of one of the fire pot sections and Fig. 4 is a rear or outside view of the same.

Like characters of reference indicate like parts throughout the several views of the drawing.

35 The walls 5 of the fire pot are in the form of an inverted hollow truncated cone deeply corrugated up and down inside and outside to increase the strength and radiating surface of the pot and to provide free straight 80 inside air passages at equal distances all around. It is preferably in two horizontally divided members as shown to reduce the chances of cracking under the action of the heat to a minimum.

45 The fire pot as above described is lined with a cast iron lining in vertically divided sections 6. These sections taper downwardly and have beveled meeting edges which hold them in the downwardly tapering fire pot without any other support than is afforded by the walls of the pot after the sections are once assembled. To aid in the assembly and also to prevent the rising of one or a group of the sections after they

have become somewhat warped and thereby loosened or loosened by the expansion of the fire pot, particularly by the shaking of the grate bars to remove ashes while the fire pot is full of cinders and coal, I provide a notch 7 in one of the vertical edges of the section 60 and provide a lug 8 of corresponding dimensions on the other edge. In assembly the lug 8 of one lining section enters the notch 7 in the section next to it, in the manner shown in the drawing, thereby locking 65 the sections together against any possible individual longitudinal movement. The weight of the lining as a whole and its tapering shape which fits in the corresponding taper of the interior of the fire pot keep the 70 lining in position in the pot.

To equalize the expansion between the lining and the fire pot I provide circulation-slots 9 between each pair of sections, formed by notching the edge of each section in half 75 the width of the whole opening, leaving the edges of the sections near the tops and bottoms of the latter intact as shown.

As the hottest part of the fire is generally midway of the height of the fire pot I 80 thicken the lining sections gradually from each end toward their middles as shown, the increased thickness being all on the inside of the section which increases the lower inside taper causing the ashes to discharge while 85 leaving the outside straight up and down; and to insure a circulation of air between the lining and the fire pot where the walls of the corrugations in the latter would otherwise contact the lining I form the lining 90 with bottom lugs 10 which hold it away as shown in Fig. 1. To additionally ventilate the top of the lining which is more exposed to the heat than the bottom portions, I provide openings 11.

95 It is obvious that one or more of the sections of the lining may be readily renewed when necessary, which will be less expensive than to substitute an entire new lining.

While I have described my invention with 100 more or less minuteness as regards details of construction and arrangement and as being embodied in certain precise forms, I do not desire to be limited thereto unduly or any more than is pointed out in the claims. On 105 the contrary, I contemplate all proper changes in form, construction and arrangement, the omission of immaterial elements

and the substitution of equivalents as circumstances may suggest or as necessity may render expedient.

I claim—

5. 1. The combination with a downwardly tapering corrugated fire pot, of a cast iron lining in a plurality of separate downwardly tapering sections said sections having spaced apart lugs next to the fire pot at their lower ends to bear against the corrugations of the pot and establish an air space, said lining as a whole being held from downward movement by the taper of the pot, and interlocking means between the sections to keep them 15 from being independently raised.
2. The combination with a downwardly tapering corrugated fire pot, of a cast iron lining in a plurality of separate downwardly tapering sections having elongated slots at 20 the joints between them and having spaced apart lugs next to the fire pot at their lower

ends to bear against the corrugations of the pot and establish an air space, each section having a lug extending across one of said slots and entering a notch in the adjacent 25 section, said lining as a whole being held from downward movement by the taper of the pot.

3. An inverted truncated conical bowl, a fire pot in a plurality of vertically divided 30 tapered sections seated in the bowl, said sections being thicker at their middles than at either end and having elongated slots at the joints between them and each section having a lug extending across one of said slots and 35 entering a notch in the adjacent section.

In witness whereof, I have hereunto set my hand and seal at Indianapolis, Indiana, this 8th day of May, A. D. one thousand nine hundred and sixteen.

OTTO M. BIRELEY. [L.S.]
